(57) **CLAIM**

The ornamental design for a seat for automobiles, as shown and described.

DESCRIPTION

1. Seat for automobiles

1.1 : is a front perspective view of a seat for automobiles; showing our new design;

1.2 : is a front view thereof;

1.3 : is a back view thereof;

1.4 : is a left view thereof, the right view being a mirror image thereof;

1.5 : is a top view thereof;

1.6 : is a bottom view thereof; and

1.7 : is a top perspective view of a seat for automobiles shown in an environment of use.

The broken lines depict portions of the seat for automobiles that form no part of the claimed design.

1 Claim, 7 Drawing Sheets
